UNITED STATES PATENT OFFICE.

FREDERIC W. POTTER, OF LOS ANGELES, CALIFORNIA, ASSIGNOR TO FITZ-EMPIRE
DOUBLE PIVOT LAST COMPANY, OF AUBURN, MAINE, A CORPORATION OF MAINE.

LATHE FOR CUTTING IRREGULAR OBJECTS.

1,362,182.

Specification of Letters Patent. Patented Dec. 14, 1920.

Application filed April 19, 1917. Serial No. 163,275.

To all whom it may concern:

Be it known that I, FREDERIC W. POTTER, a citizen of the United States, residing at Los Angeles, in the county of Los Angeles 5 and State of California, have invented certain Improvements in Lathes for Cutting Irregular Objects, of which the following description, in connection with the accompanying drawings, is a specification, like reference characters on the drawings indicating like parts in the several figures.

This invention relates to the production of irregular objects from models, such, for instance, as last lathes, gunstock lathes, hat 15 block lathes, and pattern grading machines for producing patterns for shoes, gloves, or clothing generally. The invention is herein disclosed as embodied in a last lathe, but its scope is not limited to this type of machine, 20 or to machines producing solid, as distinct from flat, objects.

The problem solved by the present invention will be described in connection with the art of last making, but it will be found, as 25 the description of the invention proceeds, that the invention has equally valuable applications in other arts, including those alluded to in the preceding paragraph.

As is well known, lasts are turned from 30 models in lathes adapted for that purpose. A whole set of lasts may be turned from a single model made by hand by a skilled workman, by the use of "grading mechanisms" which effect desired pantographic 35 reproductions of the model. The shoe manufacturer for whom the lasts are being made generally submits a sample which is nearly what he wants, asking that certain changes be made in it, and the model maker effects 40 these changes in the last by removing or adding material, in the proper places. This proceeding requires much care and time, as a discrepancy amounting to 0.02 inch will entail rejection. The resulting last, which 45 will generally be a wooden body with pieces of paper or wax sticking to it in various places, will be used as a model in a lathe for turning out an all wood duplicate which will be prepared in the ordinary manner to 50 serve as a model for producing lasts in quantities.

Often the changes required in a last in

order to produce the desired model are systematic in their nature. The shoe manufacturer may desire to have a progressive 55 change made in the shape of the last rather than a series of local corrections. For instance, he may desire to lengthen some portions of the last or to shorten others, or both. Take, for example, the moving of the ball 60 backward in the last. This will shorten the rear portion of the last and lengthen that portion which lies in front of the ball, without affecting transverse cross-sections. Such a change as this is very difficult for the 65 model maker to accomplish satisfactorily and the proper tapering off of an addition or subtraction of material along such an irregular object as a last is a matter which sometimes requires a number of trials. 70

A difficulty which is often met with in the cutting of lasts as distinct from models, arises from the demand of the shoe manufacturers that certain dimensions shall "grade" or vary by definite amounts per 75 size. The last lathe as ordinarily constructed will produce a set of lasts, all having the same width number, which will be geometrically similar solids, varying in length by 1/3 inch per size. These lasts will 80 vary by substantially 1/4 inch per size in the perimeter at the ball, waist and instep, these three measurements differing only 5/8 inch among themselves. Many manufacturers insist that the "heel" measurement 85 which is taken around the heel and over the instep, shall grade 3/8 inch per size. On most styles this measurement will grade 1/64 to 3/64 more than this, per size. The shortening of the rear part of the last relative to the forepart which can be accomplished by my invention, will enable the last maker to cut graded lasts from a model, which shall depart from strict geometrical similarity thereto in such fashion that measurements of the lasts having a substantial lengthwise component shall grade more or less rapidly than required by such similarity. 90

It is a principal object of my invention to provide for accomplishing many such results demanded by the customers of the last maker. More specifically, an important object of the invention is the production of a machine which can be used to reproduce a 100

model on a non-uniform grade, that is, which will grade different parts of the lasts produced, at different rates. Such a machine, for instance, by grading more slowly from the ball to the heel than from the toe to the ball will produce the result of moving the ball backward, alluded to in a preceding paragraph.

A feature of the invention comprises a machine having model and work holding instrumentalities, and model and work engaging instrumentalities and mechanism for effecting relative movements between corresponding instrumentalities in pairs, said movements having a velocity ratio variable during the production of the work. These "pairs" may be formed as desired. That is, they may comprise the two model instrumentalities and the two work instrumentalities, or they may comprise the two holders and the two engaging instrumentalities. The present procedure is to hold the model and work motionless as far as the direction of length grade is concerned, to produce a movement of the model wheel on the model and of the tool on the work, and to cause these movements to have an approximately constant velocity ratio. Grading, however, can, for example, be done by relatively moving the model and the work and also the model wheel and the tool, and effecting an arbitrary velocity ratio between these movements. The whole question of producing and grading such objects as those dealt with by my invention being one of relative movements between the four principal instrumentalities of the machine, the model and work holders (or holder), the model wheel or guide and the tool, I desire that my claims be construed as broadly as the prior art permits, and that they be not restricted to an interpretation dependent on the particular form of machine shown in the drawing.

Another feature of the invention is a machine having model and work instrumentalities either for holding or engaging and means for moving them at velocities having a variable ratio. Corresponding portions of the model and work are thereby dealt with at different speeds. A further feature of the invention is a machine having model and work instrumentalities and means for altering their distance from each other at a non-uniform rate during the production of the work. By the operation of such instrumentalities work may be produced having a predeterminedly systematic lack of proportion to the model.

A further feature of the invention is a machine having model and work instrumentalities and mechanism for altering their distance comprising a lever the advantage of which varies during the production of the work. A non-uniformity in the change of

relation between those instrumentalities during the work production is thereby produced.

Another feature of the invention is a machine having a model or work instrumentality which has accelerated movement during the production of the work. A non-uniformity of grading action may be produced by this means. The "acceleration" may be positive or negative.

Another feature of the invention is a machine comprising model and work holding instrumentalities, model and work engaging instrumentalities, and means for effecting relative movements between corresponding instrumentalities in pairs, said movements having a variable velocity ratio during a portion of the operation and an approximately constant velocity ratio during a portion of the operation.

The present invention may be regarded from still another point of view. The ordinary pattern copying machine may be regarded broadly as a machine for separately reproducing and then recombining a series of differential elements of the model, according to some (generally pantographic) law. In the last lathe, these elements are the transversely extending vertical slices or laminae into which a model last may be conceived as divided. These reproduced differential elements are arranged in the work in a relation corresponding geometrically in two respects to that of their prototypes in the model, viz., (1) the distances between the reproduced elements are proportional to the distances between their prototypes in the model, and (2) their relations considered transversely to the direction in which their relative distances are measured correspond geometrically to those of their prototypes.

The function of the pattern reproducing machine, as heretofore understood, has been substantially merely that of geometric reproduction of the model, and this is said without failure to recognize the fact that the work of the machine had certain distinct non-geometrical characteristics as shown, for example, in the treatment of seam allowances in the production of shoe upper patterns upon the "pattern grading" machine and in certain practices in width grading upon the last lathe involving anomalous adjustments of the model wheel (so that, for example, the front faces of the model wheel and cutter would not come into the axis of rotation in the swing frame at the same time). The reproduction of the differential elements of the model, even though it might itself be non-pantographic (non-geometric), effected substantial differences only in size, as distinguished from shape or style, owing to the fact that the reproduced differential elements were combined in the work, as

stated, in an aggregate having a geometric similarity to the corresponding aggregate of differential elements of the model. The present invention provides broadly, entirely aside from the law of individual reproduction of the differential elements, for a distinctly non-geometric relation between the arrangement of these elements in the work as compared with that of their model prototypes, thereby effecting distinct changes in shape and style as distinguished from size, and consequently bringing about large savings in the matter of model making which, as heretofore practised, has been a very expensive hand labor proposition. In the machine shown, the distances between the reproduced elements are rendered non-proportional to the corresponding distances in the model by a non-uniformly acting length grading mechanism. While I have selected this type of re-arrangement of the reproduced elements for illustrative purposes, this does not import a limitation of the invention to this particular embodiment as the invention may be carried out in other ways, for example, by sliding the reproduced elements upon one another as described in the application of L. B. Whipple, entitled "Manufacture of articles having a systematic resemblance to a pattern," Ser. No. 185,104, filed Aug. 8, 1917, renewed as Ser. No. 252,122, filed Aug. 30, 1918.

Another important feature of my invention resides in the provision of convertibility. My machine can be adjusted so that its action corresponds exactly to that of the commercial machines at present in use. It can thus be converted from an ordinarily grading machine to a non-uniformly grading machine, and can therefore be kept running all the time at one kind of work or the other.

These and other features of the invention comprising various combinations and arrangements of parts will be best understood and appreciated from the following description of a preferred embodiment thereof in a last making machine selected for purposes of illustration and shown in the accompanying drawings in which,

Figure 1 is a front elevation of the machine;

Fig. 2 is a plan, partially in section, of the novel grading mechanism;

Fig. 3 is a front elevation of a portion of the grading mechanism;

Fig. 4 is an enlarged sectional plan of a portion of the grading mechanism taken on the line 4—4 of Fig. 1;

Fig. 5 is a section on the line 5—5 of Fig. 3;

Fig. 6 is a sectional elevation on the line 6—6 of Fig. 3;

Figs. 7 to 12 inclusive are diagrammatic

illustrations of a mode of operation of the machine; and

Figs. 13 to 18 inclusive are diagrammatic illustrations of the operation of the machine with a different adjustment.

The main frame 2, the swing frame 4, the width grading mechanism 5, the cutter carriage 6, the model wheel carriage 8 and the driving mechanism for the model and the block and the carriages are all of ordinary construction and need not be further described. The cutter 14 is directly geared to the shaft of a motor 16 in order that it may be revolved at a very high speed and be free from vibration due to belt transmission and is of peculiar construction having its axis of rotation inclined toward and with the direction of travel of the cutter carriage. The model wheel 18 is a spherical ball corresponding in dimensions to the nose of the cutter 14. The model wheel and cutter form no part of the present invention and need not be further described.

Mounted on the frame of the machine is a bar 20 which extends diagonally downward and is braced to the frame by a horizontal brace 22. Adjustably clamped to this bar by means of the bolts 24 and a plate 25 is a member 26 having in it a vertical slideway 28. In this slideway a slide 30 is arranged for free vertical movement, and has mounted in it a stud 32. The stud 32 has an enlarged bearing portion 34 adapted to receive pivotally the end of a link 36 the purpose of which will be described later. Next to the link 36 on the stud 32 is pivotally mounted a radius block 38 in which is fixedly mounted a stud 40. The stud 40 is threaded and carries a nut 42 the purpose of which is to clamp the length grading lever 44 tightly to the radius block 38. The studs 40 and 32 extend through a long slot 46 in the grading lever. The stud 32 has on its end a nut 48 which draws the members 44 and 38 against the shoulder on the bearing 34, though not so tightly as to prevent pivotal movement there. This construction permits the lever 44 to be adjusted up and down and to have, at the same time, a pivotal movement about the center of the stud 32, the lever being clamped firmly to the radius block 38 and the radius block rotating upon the stud 32.

The upper end of the lever 44 is slotted front and back, and in the rear slot 50 carries a slidably mounted block 52. A thumb screw 54 is provided for clamping the block 52 in any adjusted position in the slot 50 for a purpose which will appear later. The front slot 56 in the lever carries a block 58 which may be adjustably clamped therein by the thumb screw 60 mounted in a U-shaped clamp 61 extending around the lever 44. Pivotally mounted in the block 52 is

a stud 62 which is fixedly mounted in the model wheel carriage 8. The block 58 carries a stud 64 upon which is pivotally mounted the end of a link 66 having a 5 length adjustment at 68 and pivotally mounted at its other end upon a stud 70 fixedly mounted in the cutter carriage.

Pivoted at 71 upon a block 72 which is slidably adjustable on a bar 73 10 mounted on the main frame and extending parallel to the bar 20, is a segment 74 having a slot 76. This slot is preferably an arc of a circle passing through the point 71. Slidably and adjustably mounted in this 15 slot is a block 78 to which is pivotally connected at 79 the upper end of the link 36 before mentioned. The link 36 has a length adjustment at 80. An upwardly projecting arm 81 of the segment carries two ears 82 20 and 84 so arranged as to be vertically movable on guides 86 and spaced at such a distance that a stud on some part of the power driven mechanism which may conveniently be the stud 62 just fits between them when 25 they are both projecting upwardly from the arm 81 in their uppermost positions on the guides 86. The bolts 88 clamp them in adjusted position on these guides.

Two adjustable stops 90 and 92 are arranged for sliding horizontal adjustment on 30 the main frame by means of the bolts 94 and are arranged to contact the arm 81 of the segment when suitably positioned. Their range of adjustment is sufficient to 35 permit their being placed out of the normal path of the segment arm 81 when desired. A spring 96 is arranged to be connected to either of two hooks 98 at the ends of the segment and to the bottom of the bar 20. 40 It is contemplated that all the adjustments of the lathe will be supplied with conveniently graduated scales to facilitate their use. Such scales may be interchangeable for different sorts of work. Their graduation 45 may be largely empirical.

If it is desired, for instance, to make a last similar to a given model, but in which the length is graded at a progressively slower rate from the toe to the heel, the block 78 50 will be placed in a suitable position in the left half of the slot 76. The thumb screw 54 will be loose and the thumb screw 60 will be tightly holding the block 58 in adjusted position in the slot 56. The stops 90 and 55 92 are both slid back from the segment and the ears 82 and 84 are extended, clamping the stud 62. When the cutting begins at the toe, the stud 70 will push the model wheel carriage to the left by means of the link 66, 60 the lever 44 and the stud 62. The stud 62 as it moves to the left will exert pressure upon the finger 82 thereby rotating the segment 74 about its pivot 71 in the ear 72. This rotation of the segment 74 will carry 65 85 downward the link 36 which, through the

bearing 34, will lower the slide 30 in the slideway 28. This movement of the slideway will carry downward the block 38 and the lever 44 which is rigidly clamped thereto but is free to rotate about the center of the 70 axle of the stud 32. As the lever descends, rotating at the same time, it carries with it the block 58 which is rigidly clamped to it. The block 58, as has been remarked, carries the left end of the link 56 at 64. It will be 75 evident then, that the movement of the stud 62 with regard to the moving center 32 about which the lever 44 rotates is upon an arc of continually increasing radius, while the movement of the stud 64 with regard to the 80 center 32 is upon an arc of constant radius, the studs 32 and 64 having an invariable relation to each other on the lever. In other words, the "advantage" of the lever as regards the studs 62 and 64, is continually 85 changing. It results, therefore, that the model wheel carriage will accelerate or move to the left more and more rapidly as the cutter carriage moves to the left, preferably at uniform velocity. It is thus apparent 90 that equal segments of the block, measured longitudinally, correspond to segments of continually increasing length on the model; or, which is the same thing; that equal segments of the model, measured longitudinally, correspond to continually decreasing segments of the block. The heel portion of the last cut will be proportionally shorter than the toe portion.

Figs. 7 to 12 inclusive illustrate this operation diagrammatically. Fig. 7 shows the adjustment so made that the pivot 64 at the beginning of the turning is below the stud 62 on the lever 44. Fig. 8 shows the condition of things when the turning has proceeded a short distance from the toe. The lever 44 has descended, because of the rotation of the segment 74, carrying with it the pivot 64. Figs. 9, 10 and 11 show three later positions in the operation. Fig. 12 105 shows in its upper line the movements executed by the model wheel carriage between the positions represented by Figs. 7 to 11, and in its lower line the corresponding movements of the cutter carriage. The 110 points marked 7, 8, 9, 10 and 11 in the two lines correspond to the positions occupied by cutter carriage and model carriage at the instants corresponding to Figs. 7 to 11 respectively, the scale, however, being doubled 115 in order to make the operation more clear. It will be noticed that the spaces on the upper line are equal, the figures having been plotted to correspond to the quarter points in the length of the model. It is clear that 120 the cutter carriage between the points 7 and 8 has moved a shorter distance than the model carriage and that it is moved a still shorter distance between the points 8 and 9 than has the model carriage and so on, 130

so that the grading of the last cut grows progressively shorter from the toe to the heel. The ratio between the velocity of the model wheel relative to the model and 5 the velocity of the cutter relative to the block, or, as I have termed it in the appended claims, the "velocity ratio" of these two relative movements, is a continually increasing one. In ordinary grading such 10 velocity ratio is desired to be constant, and in reproduction of the same size the ratio is unity.

Figs. 13 to 17 show a corresponding series of positions obtained with another adjustment of the parts and Fig. 18 illustrates the corresponding movements of the cutter and model carriages. This series of figures shows how a last may be cut having the same over-all length as the model but graded 15 longer at the toe and shorter at the heel, the notation and scales corresponding to those of the previously discussed series of figures. It will be seen that the cutter carriage moves faster than the model carriage at the beginning 20 of the cutting and gradually slows down so that at the end of the cutting it is moving more slowly than the model carriage, the arrangement being such that the over-all traverse of the two carriages is the 25 same.

A result analogous to that described above, may be produced by another mode of operation of my lathe, which more nearly resembles the operation of the machine here- 30 tofore known. The screw 54 is set, firmly clamping the block 52 in the lever 44, which thus becomes suspended from the model wheel carriage as under the ordinary practice. The nuts 42 and 48 are loosened suffi- 35 ciently to permit the lever 44 to slide freely relative to the studs 32 and 40. The segment will be actuated exactly as above de- 40 scribed, but the link 36 will now carry downward only the pivot 32 when the slide 45 30 descends. This will cause both the studs 62 and 64 to move relative to the center 32 upon arcs of continually increasing radii and so that the ratio of the radii will be continually changing. The advantage of the lever 50 relative to the studs is therefore variable during the last-cutting, but in a different manner.

The two radii become more and more nearly equal as the cutting proceeds, and 55 with the particular adjustment described, the cutter carriage therefore moves slower than the model wheel carriage, but gains constantly in velocity relative to it. The result is then opposite to that of the first 60 described operation. A result like the former in kind but differing in degree can of course be obtained by shifting the block 78 to the other side of the segment 74.

In this connection a valuable application 65 of my invention to the turning of lasts as

distinct from models, may be described. Lasts are generally graded so that they increase 1/4 inch per size at the ball, waist and instep. Some shoe manufacturers insist that the measurement around the heel and 70 instep be taken also, and that this measurement increase 3/8 inch per size. With many models, this measurement will increase more than 3/8 inch per size when the cutting is done in the ordinary last lathe. It is clear 75 that the shortening of the rear part of the last and the corresponding lengthening of the forepart accomplished by my invention will meet this difficulty, since the girth measurements at the ball, waist and instep will 80 be unaffected. I accomplish the desired result as follows:

The stud 64 is adjusted above the stud 62, which will be assumed fixed in the lever, the fulcrum 32 consequently being arranged 85 to slide in the lever, and the link 36 is placed on the left as shown in Fig. 3. In the ordinary Gilman lathe the length grading scale is graduated 7/8 inch per size graded up or down from the model. Denote by a 90 the distance between the pivots 62 and 32 when the lever 44 is vertical. (In ordinary turning with a 10 inch model this distance is about 26 1/4 inches). Denote by b the distance the pivot 32 is dropped by the segment mechanism, and by m the length of the model. Denote the 7/8 inch graduation interval by g . Then, if the pointer is set up n 95 graduations, for an n size grade, the average rate of magnification will be: 100

$$\frac{1}{2} \left[\frac{\frac{a-b}{2} + ng}{a-\frac{b}{2}} + \frac{\frac{a+b}{2} + ng}{a+\frac{b}{2}} \right] \quad 105$$

and the length of the last cut will be

$$\frac{m}{2} \left[\frac{\frac{a-b}{2} + ng}{a-\frac{b}{2}} + \frac{\frac{a+b}{2} + ng}{a+\frac{b}{2}} \right] = m + \frac{n}{3} \quad 110$$

the grading of the last being 1/3 inch per size. This equation reduces to 115

$$a^2 - 3agm - \frac{b^2}{4} = 0$$

This gives the relation between the quantities a , b , g , m which must be satisfied if a 120 whole set of lasts are to be graded with the g scale, with their foreparts graded longer than their rear parts by means of my invention. For instance suppose a ten-inch model is being used; we substitute the values 125 of m and g in the above and obtain

$$a^2 - 26\frac{1}{4}a - \frac{b^2}{4} = 0$$

a and b can be changed simultaneously by 130

- the adjustments at 79 and 80. The adjustment which will give the desired irregularity of grade will have to be found by trial, as the value of b will be found to vary with different styles in order to give the desired 3/8 inch grade in the heel measurement. The variations in a will be very small. If b equals 0, a equals $26\frac{1}{4}$, as stated above; if b equals 5, a is between 26.48 and 26.49.
- 10 This change is far within the limits within which the grading scale itself can be relied on. It is well known that the adjustments in a last lathe need a good deal of "jockeying" with models of different styles, and
- 15 the above demonstration is to be regarded merely as a first approximation to an empirical solution. It shows, however that the solution is possible.

Another mode of operation of the machine will now be described. Let the ear 84 be dropped as shown in Fig. 3 so that it cannot contact with the stud 62 and suppose the stop 92 to be so adjusted that the spring 96 holds the segment against it in the position shown in Fig. 3, the adjustments of the screw 54 and the nuts 42 and 48 being as in the first described operation. At the beginning of the cutting the stud 62 will be in the dotted position to the right indicated in Fig. 3. As the cutting proceeds from the toe the stud 62 will move to the left but the segment 74 will remain motionless since the stud 62 is not in contact with either ear 82 or 84. The pivot 32 will remain motionless and the lever 44 will simply swing about it. The stud 62 will of course move in a horizontal direction with its carriage 8 while the stud 64 will move in a circle of large radius around the stud 32 as center. The distances of the studs 62 and 64 from the stud 32 will not, however, change very much during this part of the cutting and the grading from the toe up to the point when the stud 62 comes in contact with the ear 82 will be substantially uniform. When the stud 62 reaches the ear 82 the segment will begin to rotate and the rate of grade will begin to change as has been described. A lathe when adjusted in this way will cut a last having a substantially constant or zero grade in the forepart and having a variably graded heelpart.

By adjusting the screw 54 and the nuts 42 and 48 as in the second described operation, the lathe will grade exactly in accordance with the practice heretofore known until the stud 62 picks up the ear 82. This grade will be more nearly uniform in its uniform portion than that just described.

60 It is possible, of course, by dropping both ears 82 and 84, to make my machine the entire equivalent of the ordinary lathe. It will thus be clear that my invention has produced an exceedingly flexible machine which embodies every possibility of the ordinary

machine, and in addition is capable of producing a wide range of irregular grading operations.

If the stop 92 is moved to extreme right-most position and the stop 90 advanced to the right to contact with the upper arm of the segment, the ear 82 dropped and the ear 84 raised, and the spring 96 moved to the other side of the segment the lathe will cut a last which is non-uniformly graded in the forepart and substantially uniformly or zero graded in the heelpart. It has been proposed to mount interchangeable last foreparts on standard heelparts, and the advantage of my invention in connection with such a system of last making will be obvious.

While I have described and shown the ears 82 and 84 as placed in position in the path of the stud 62 before the cutting operation begins, I regard a construction in which an ear is automatically projected into connection with a power driven member at a predetermined time, as within the scope of my invention.

It will be evident that the spring 96 may be used as the driving means of the segment at all times, by placing it on the left side of the lever. The stud 62 will then merely control the movement of the segment.

A few general remarks covering the adjustments of my apparatus may not be out of place. It is well known from existing practice that the last cut is graded longer or shorter than the model according as the stud 64 is above or below the stud 62 during the cutting. When the block 78 is to the left of the center 71, the pivot 64 will be lowered at a rate dependent on the distance of the block from the center 71. When the block 78 is adjusted on the right arm of the segment, the pivot 64 will be raised as the cutting proceeds. When the block 78 is centrally adjusted on the segment, there will be no vertical movement of the lever 44, and the pivot 64 will move vertically only to the extent compelled by purely circular movement. The link 36 is shown of the same effective length as the radius of curvature the slot 76, but the adjustment 80 permits a variation of this length. The adjustment of the member 26 on the bar 20 permits the placing of the pivot 32 at any desired distance from the other two fulcra of the lever, and thus has an effect on the rate of grade.

The purpose of the adjustment of the pivot corresponding to 32 in the ordinary lathe along the diagonal bar 20 is to enable the operator to align this pivot with the center of the model when the length of the model is changed. It will be noticed that as the model shortens, the pivot, in following its center to the left, rises along the bar 20. This causes a greater relative movement of the pivots 62 and 64 which corresponds to the greater relative differences in length

between a short model and its adjacent sizes, due to the fact that the total shortening per size remains $1/3$ inch. It will be remembered that the relative position of the pivots 5 62 and 64 for the same number of sizes change in grade will be the same for a short model as for a long one, since the same adjusting scale is used on the lever. It is therefore necessary to move the lower pivot. 10 The adjustment of the pivot 71 along the parallel bar 73 enables the operator to keep the pivot 71 directly above the pivot 32 and alined with the center of the model. It will not always be necessary to have 15 these pivots so alined in model making, and, in some cases such practice may be found inadvisable. This adjustment adds another degree of flexibility to the machine. The failure to aline those pivots with the center 20 of the model will cause an inequality of action on the fore and heel parts of the last cut.

Further, the lack of parallelism in the movements of the link 66 is of considerable 25 importance in my novel apparatus. When the link 66 is approaching a horizontal position, *i. e.*, when the pivot 64 is approaching the level of the pivot 62 from above or below, the stud 70 has a smaller movement 30 in a given interval than the horizontal component of the corresponding movement of the stud 64, and vice versa. All the effects mentioned may be cumulative or differential, according to circumstances, and 35 the machine by proper adjustment, may be made to produce a wide variety of results.

While in this country it is the universal practice to mount the model and the work co-axially at a fixed distance from each 40 other and to grade by controlling the movements of the tool and model wheel relative to the block and to the model and to each other, it is quite possible to cut and grade lasts by machines otherwise constructed. 45 All that is necessary is to effect a relative movement between the model wheel and the model and between the cutter and the block and also a relative movement between two of these objects, one from each of the pairs. 50 I intend that the terms "model instrumentality" and "work instrumentality" in the claims shall be broadly interpreted to mean 55 respectively either member of the pair which work on the "model side" of the machine, namely the model wheel carriage and the model holder; and either member of the pair which operate upon the "work side" of the lathe, namely the cutter and the work holder. and that these terms shall not be 60 limited to either specific member of these pairs of operating instrumentalities unless required, in the case of any particular claim, by the prior art.

As already pointed out above, this invention can be regarded from a radically dif-

ferent point of view. The pattern copying machine, various forms of which are known for reproducing patterns or models of three or less dimensions, may be regarded fundamentally as a mechanism for first, reproducing differential elements into which the model may be regarded as divided, and, second, putting together these reproductions in the work. For example, the ordinary last lathe in one aspect may be regarded 70 as; 1, dividing (in effect) the model into a series of slices (differential elements) of thickness equal to the feed per revolution of the model; 2, reproducing each element or slice by multiplying each radius vector from 75 its center of rotation (the pole, so-called) by the width grading ratio (in case of pantographic reproduction), and plotting all these magnified radii from the corresponding pole in the block; 3, arranging 80 all these reproduced differential elements in order (a) with their poles in the axis of rotation in the block and (b) so that their distances from one another parallel to the axis of rotation are proportional to the 85 corresponding distances in the model.

My invention can be regarded generically as reproducing differential elements (the laminæ of the illustration in the preceding paragraph) and altering their relative 90 positioning so as to produce a lack of geometric correspondence between the arrangement in the work and the arrangement in the model. In that branch of the problem dealt with by the present machine, 100 with the machine as ordinarily arranged (with the cutter carriage fed uniformly and driving the model wheel carriage through the length grader), the reproduced laminæ will be uniformly spaced in the work along 105 the axis of rotation (which extends substantially perpendicular to them, and along which their distances from one another are measured) and their model prototypes will be non-uniformly spaced, and will exhibit 110 rarefactions and condensations in arrangement. The want of geometric correspondence between the two arrangements is apparent. It is obvious that either arrangement may be regarded as out of proportion 115 to the other.

I have used the term "model wheel" in a generic sense, intending thereby any member which follows the model in order to control the operation of the machine. In 120 American practice such a member is generally an idler wheel.

I wish to emphasize distinctly that although I have illustrated my invention embodied in a last lathe length grading apparatus, I do not consider it to be limited to such apparatus. I consider a width grading mechanism which grades non-uniformly at different points on the same periphery or on different peripheries of a last or at dif- 125 130

ferent points on a pattern to be fully within the scope of my invention, and I intend that the appended claims shall be construed to cover any such machine upon which their 5 terms read.

The term "space relation" as applied to the model wheel and model, for instance, in such a machine, would refer to the varying distances between the wheel and the axis of 10 the model; whereas, in such a machine as I have shown, the term refers to the longitudinal traverse of one object on the other.

The action of the length grading mechanism as it has been disclosed herein is entirely independent of the action of the width 15 grader 5; either may be used independently of the other, or both may be used together.

Broadly, I believe any predeterminedly non-uniformly acting or "accelerating" 20 grading mechanism on any machine for reproducing irregular forms, either plane or solid, which is covered by the appended claims when their terms, such for instance, as "model," "model wheel," "block," "work," 25 "cutter," "last," "cutting," "space relation," etc., are given a generic interpretation is included within the scope of the present invention.

The utility of the invention in connection 30 with machines for making all sorts of articles intended for individual use, will be apparent. The user of a shot gun is as particular about the "fit" of his gunstocks as he is about that of his gloves. Thousands 35 of golf clubs are made to order every year for the purpose of securing slight individual differences of contour in the heads. Individual patterns for clothing of all sorts, and artificial limbs may be satisfactorily and 40 cheaply produced by means of my invention.

All the articles mentioned, among others, are produced on pattern copying machinery operating on the generic principle of the last lathe.

Having described the invention, what I 45 claim as new and desire to secure by Letters Patent of the United States is:

1. A machine of the class described having 50 model and work holding instrumentalities, and model and work engaging instrumentalities, and mechanism for effecting relative movements between corresponding instrumentalities in pairs, said movements having a velocity ratio which is variable during the 55 cutting of a last.

2. In a machine of the class described, a 60 model wheel carriage, a cutter carriage, a model holder and a work holder, and mechanism constructed and arranged to effect relative movements between the first and third and between the second and fourth of said instrumentalities, said movements having a velocity ratio variable during the cutting of a last.

65 3. In a machine of the class described, a

model wheel carriage, a cutter carriage, a model holder and a work holder, and mechanism constructed and arranged to effect relative movements between the first and third and between the second and fourth of 70 said instrumentalities, comprising a linkage the effective length of which is variable non-uniformly during the cutting of a last.

4. In a machine of the class described, a model wheel carriage, a cutter carriage, a 75 model holder and a work holder, means for simultaneously effecting varying space relations between the first and third and between the second and fourth of said instrumentalities, corresponding space variations 80 having a non-uniformly varying relation to each other during the cutting of a last.

5. In a machine of the class described, a model holder, a work holder, and a model follower and a cutter, arranged to contact 85 with a model and a block carried respectively by said model holder and work holder, and means for simultaneously carrying the points of contact of the model and follower and of the cutter and the block along the 90 model and block respectively, the ratio of corresponding movements of said points of contact being variable during the turning of a last.

6. In a machine of the class described, a 95 model holder, a work holder, a model follower and a cutter, means for carrying the point of contact of the model and follower along the model, means for simultaneously carrying the point of contact of the work 100 and the cutter along the work, the velocities of the said points of contact having a ratio variable during the turning of a last.

7. In a machine of the class described, a model wheel and a cutter, a model and a 105 block, means for effecting relative traverses between the corresponding members of the said pairs of instrumentalities and means for effecting a varyingly determinable non-uniform relative movement between the 110 members of one of said pairs of instrumentalities.

8. In a machine of the class described, a model wheel carriage, a cutter carriage, and mechanism for moving said carriages at a 115 variable velocity ratio during the cutting of a last.

9. In a machine of the class described, a carriage and means for moving said carriage continuously in the same direction at a variable velocity during the turning of a last. 120

10. In a machine of the class described, a model instrumentality, a work instrumentality, and means for altering the distance between said instrumentalities at a 125 variable rate during the cutting of a last.

11. In a machine of the class described, a model carriage, a work carriage, means for driving one of said carriages and a second driving means connecting said carriage 130

- with the other carriage, the driving action of said means having a varyingly determinable non-uniform time rate.
12. In a machine of the class described, 5 a model instrumentality, a work instrumentality, means for driving one instrumentality, and means connecting the two instrumentalities for simultaneous movement, said means having an effective length which 10 varies non-uniformly according to an arbitrary law during the turning of a last.
13. In a machine of the class described, 15 a moving model wheel carriage, a moving cutter carriage, an instrumentality connecting said carriages and means for effecting a relative movement of the points at which said instrumentality is connected to said carriages, said movement being varyingly and determinably non-uniform as compared 20 with the movement of one of said carriages.
14. In a machine of the class described, 25 a carriage on the model side of the machine, a carriage on the work side of the machine, a member connected to both of these carriages and means for effecting relative movement on this member between its two points through which connection is made to the carriages, during the turning of a last, in order to bring about a non-uniform 30 relative movement of the carriages.
15. In a machine of the class described, 35 a model wheel instrumentality, a work instrumentality, an angularly moving member connected to both of these instrumentalities, and means for effecting relative movement of the two points of connection on the angularly moving member during the turning of a last.
16. In a machine of the class described, 40 a carriage on the model side, a carriage on the work side, a member connected to both of these carriages and means operated by one of the carriages for effecting relative movement between the two points of connection on the member during the turning of 45 a last.
17. In a machine of the class described, 50 relatively moving carriages, a length grading device for producing the relative movement and mechanism for varying automatically the grading effect during the grading operation.
18. In a machine of the class described, 55 relatively moving carriages, a grading device for controlling their relative movement, and a mechanism for variably controlling the grading device operated by the movement of a carriage.
19. In a machine of the class described, 60 65 relatively moving carriages, a grading device for controlling their relative movement, and a mechanism for varying the operation of the grading device operated in time relation to the progressive performance of the work.
20. In a machine of the class described, 70 two carriages, means for operating them during the progressive performance of the work, a grading device for controlling their relative movement, means for variably controlling the grading device and a member for operating the controlling means arranged for operation by a carriage during a portion of the operation of the machine.
21. In a machine of the class described, 75 80 two carriages, means for operating them during the progressive performance of the work, a grading device for controlling their relative movement, means for varying the operation of the grading device, means for operating the controlling means and means for controlling its operation by the movement of a carriage.
22. In a machine of the class described, 85 a plurality of moving carriages, a grading mechanism for controlling their relative movement, and a controller for variably operating the grading mechanism having a part constructed and arranged to be projected into the path of movement of a moving part for actuating the controller.
23. In a machine of the class described, 90 a model wheel carriage, a cutter carriage, a drive for one carriage, and a connection between the carriages comprising a lever the advantage of which varies substantially during the turning of a last.
24. A machine of the class described having model and work instrumentalities and means for altering their distance comprising a lever the advantage of which is variable during the turning of a last.
25. In a machine of the class described, 95 a carriage on the model side of the machine, a carriage on the work side, a connection between the carriages comprising a lever, and means operated by one of the carriages for varying the advantage of the lever during the cutting of a last.
26. In a machine of the class described, 100 105 a model instrumentality, a work instrumentality, and mechanism connecting them comprising a lever having a fixed point of connection to each instrumentality, a pivot for the lever, mounted on the frame, and means for moving said pivot during the production of the work.
27. In a machine of the class described, 110 a model instrumentality, a work instrumentality, a lever having two of its fulcra connected to these instrumentalities respectively, and means for varying the distance between these fulcra during the turning of a last.
28. In a machine of the class described, 115 120 a model instrumentality, a work instrumentality, and a grading lever between said instrumentalities, having a fulcrum connected to each, and having a fulcrum, fixed in the lever, on the frame of the machine, the 125 130

lever having a longitudinal movement and carrying said last-named fulcrum and one other, but not the third, therewith during said movement, so that a shift of leverage 5 occurs as between the two first-named fulcra.

29. In a machine of the class described, a model wheel carriage, a cutter carriage, and a lever pivotally connected to each, said 10 lever having a pivot moving toward or from a first mentioned pivotal connection during the turning of a last to vary the advantage of the lever.

30. In a machine of the class described, 15 a carriage on the model side, a carriage on the work side, and means for relatively moving said carriages comprising a lever rotatable about a fulcrum moving with relation to the connections to the said carriages 20 during the turning of a last, to vary the leverage of one with reference to that of the other.

31. In a machine of the class described, a model instrumentality, a cutter instrumentality, a grading lever having two of its 25 fulcra connected to the carriages respectively, the distances between these fulcra and the third fulcrum being variable and invariable, respectively during the turning 30 of a last.

32. In a machine of the class described, a model wheel carriage, a cutter carriage, and a grading lever between said carriages having three moving fulcra, whereby the 35 advantage of the lever as between the carriages may be altered as it swings.

33. In a machine of the class described, a 40 grading lever having three pivots moving in such manner as to vary the advantage of the lever as between the carriages, the movements of two of said pivots being controlled by that of the third.

34. In a machine of the class described, a model wheel carriage, a cutter carriage, and a 45 grading lever connecting the carriages and having one of its fulcra operatively connected to one of the carriages for movement to vary the mechanical advantage of the lever as between the carriages as 50 the operation of the machine proceeds.

35. In a machine of the class described, a model wheel carriage, a cutter carriage, and a 55 grading lever having two of its fulcra connected to one of the carriages and its third fulcrum connected to the other carriage, one of the fulcra being connected for reaction against the machine frame whereby one of the two fulcra may be moved independently of its movement in the line of 60 travel of the carriage to vary the advantage of the lever as between the carriages.

36. In a machine of the class described, two carriages, a grading lever, two pivots connected to the carriages respectively, a

third pivot on the frame, and means for 65 interchangeably adjustably or slidably connecting the lever to each of said pivots, whereby ordinary or quite non-uniform grading action may be secured as desired.

37. In a machine of the class described, a 70 pivot on the main frame, carriages on the model side and on the work side, a plurality of pivots connected to the carriages, respectively, and a lever arranged for slid- 75 able connection to two of said pivots, whereby, at the will of the operator, the machine may be adjusted to grade in the ordinary way, or systematically non-uniformly.

38. In a machine of the class described, 80 two carriages, a grading lever, two pivots connected to the carriages respectively, a third pivot on the frame, and means for slidably connecting the lever to each of said pivots, whereby the lever may be rendered of variable advantage as between the carriages 85 or ordinary in its action, at will.

39. In a machine of the class described, a model wheel carriage, a cutter carriage, mechanism operatively connecting the carriages comprising a lever to which both are 90 connected, and means independent of the connecting means operated by the movement of one carriage for controlling the relation of the lever to the carriages.

40. In a machine of the class described, a 95 model carriage, a cutter carriage, a grading lever connecting the carriages, and means operated by one of the carriages for varying the position in space of a fulcrum of the lever, whereby the advantage of the 100 lever as between the carriages is varied during the cutting of a work piece.

41. In a machine of the class described, a model carriage, a cutter carriage, and a 105 grading mechanism connecting the carriages comprising a lever having a fixed fulcrum and controlled by a carriage, and a second lever having two fulcra connected to the carriages respectively, and regulated as to fulcrumage by the first mentioned lever. 110

42. In a machine of the class described, a model wheel carriage, a cutter carriage, and a grading instrumentality connecting said carriages comprising a lever controlled by one carriage and a second lever regulated 115 in advantage, as between the carriages by the first mentioned lever and a carriage.

43. In a machine of the class described, a model instrumentality, a work instrumentality, a grading lever having fulcra operatively connected to the instrumentality 120 respectively and means controlling another fulcrum for effecting relative movement between the first mentioned fulcra.

44. In a machine of the class described, a 125 model wheel carriage, a cutter carriage, a grading lever having fulcra operatively connected to the carriages respectively and

means controlling another fulcrum for moving one of the first mentioned fulcra along the lever.

45. In a machine of the class described, a model wheel carriage, a cutter carriage, a lever controlled by one of said carriages, and a second lever suspended on the first lever, and operatively connected to both carriages.

10 46. In a machine of the class described, a model instrumentality, a work instrumentality, a grading lever connecting said instrumentalities and means for rotating said lever at a substantially non-uniform angular velocity during the turning of a last.

15 47. In a machine of the class described, a model wheel carriage, a cutter carriage, a grading lever connecting said carriages, and means for rotating said lever at an angular velocity substantially disproportionate to the velocity of one of said carriages.

20 48. In a machine of the class described, a model instrumentality, a work instrumentality, a member connecting them and arranged to produce relative movement between them, and means for moving said member with a substantial angular acceleration during the cutting of a last to produce the relative movement.

25 49. In a machine of the class described, a model wheel carriage, a cutter carriage, a lever pivotally connected to each, and means for changing the operative relation of the lever to the carriages comprising mechanism for lifting said lever bodily during the turning of a last.

30 50. In a machine of the class described, a model wheel carriage, a cutter carriage, a lever connected to each, a slide mounted on the frame of the machine, and containing a fulcrum of said lever, and means moving said slide during the turning of a last.

35 51. In a machine of the class described, a model wheel carriage, a cutter carriage, a lever connected to each, and a slide mounted on the frame of the machine, and containing a fulcrum of said lever, said slide being operatively connected with one of said carriages for moving said fulcrum.

40 52. In a machine of the class described, a model wheel carriage, a cutter carriage, a lever connected to each, a slide mounted on the frame of the machine, and containing a fulcrum of said lever, and a lever controlled by one of said carriages and connected to said slide.

45 53. In a machine of the class described, a plurality of moving carriages, and a lever connecting said carriages constructed and arranged to rotate about a moving fulcrum fixed in the lever and not connected to either of said carriages, and means for moving the fulcrum.

50 54. In a machine of the class described, a

plurality of moving carriages, and a lever 65 connected to the carriages at different points for altering their distance and constructed and arranged to move as a whole transversely to its line of action on the carriages to alter the relative locations of its fulcra 70 whereby its advantage is varied during the production of a work piece.

55. A machine of the class described having movable model and work instrumentalities, a connection between them comprising a lever and means for controlling their relative movement comprising a segment and a link having one end adjustably mounted on the segment and having its length substantially equal to that of the radius of curvature of the segment and carrying a fulcrum of the lever at the end remote from the segment.

60 56. In a machine of the class described, a carriage on the model side, a carriage on the work side, and grading mechanism comprising a fulcrum on the frame, a fulcrum on one carriage, a fulcrum connected to the other carriage, and a lever carrying said latter fulcrum and arranged to be slidably or 90 fixedly connected to either of the other fulcra.

65 57. In a machine of the class described, a model holder and a model follower, a work holder and a cutter, means for effecting 95 relative traverses between the members of each of said pairs of instrumentalities at an approximately constant velocity ratio during a portion of the turning of a last, and at a substantially variable velocity ratio during 100 a portion of the turning of the last.

70 58. In a machine of the class described, a model and a model wheel, a block and a cutter, means for moving the point of contact of the model and wheel along the model, and 150 for moving the point of contact of the block and cutter along the block, corresponding movements of said contact points having a predetermined approximately constant ratio during a part of the turning of a last and a 110 substantially variable ratio during a part of the turning of the last.

75 59. In a machine of the class described, a model carriage, a cutter carriage, means for driving said carriages at an approximately 115 constant velocity ratio during a portion of the turning of a last, and at a substantially variable velocity ratio during a portion of the turning of the last.

80 60. In a machine of the class described, a model instrumentality, a work instrumentality, means for driving said instrumentalities at an approximately constant velocity ratio during a predetermined portion of the cutting of a last and at a substantially variable velocity ratio during a predetermined portion of the cutting of the last.

85 61. In a machine of the class described, a

model wheel carriage, a cutter carriage and means for varying the distance between said carriages at an approximately uniform rate during a portion of the cutting of a last and at a substantially non-uniform rate during a portion of the cutting of the last.

62. In a machine of the class described, a model wheel carriage, a cutter carriage, and a mechanism connecting them constructed and arranged to alter its effective length at an approximately uniform rate during a portion of the cutting of a last and at a substantially non-uniform rate during a portion of the cutting of the last.

63. In a machine of the class described, a model instrumentality, a work instrumentality, a lever connected to them, and means for rotating the lever at approximately constant advantage during a part of the turning of a last, and at substantially varying advantages during a part of the turning of a last.

64. In a machine of the class described, a model wheel carriage, a cutter carriage, a lever connected to them at different points, and means for substantially varying the distance between the points of connection during a portion of the turning of a last.

65. In a machine of the class described, a model wheel carriage, a cutter carriage, a grading lever connecting them, and having a point of connection with one of them, movable on the lever, and means for substantially moving this point during a part of the cutting of a last.

66. In a machine of the class described, a model wheel carriage, a cutter carriage, a lever connecting them and arranged to alter their distance by rotating, and means for effecting translational movement of the lever during a part of the cutting of a last, whereby the advantage of the connection to the carriages may be altered.

67. In a machine of the class described, two carriages, a grading device connecting them, mechanism for varying the uniformity of grade while the work is being formed, and means for rendering said mechanism inactive during a portion of the work forming operation.

68. In a machine of the class described, two carriages, a grading device connecting them, mechanism for varying the uniformity of grade while the work is being formed, and means for placing said mechanism in operative relation to said device during a part of the work forming operation.

69. In a machine of the class described, two carriages, a grading mechanism connecting them, a mechanism for controlling the regularity of the grade and means for starting or stopping said controlling mechanism at a predetermined time during the work forming operation.

70. In a machine of the class described, actuating mechanism, two relatively moving carriages, a grading device for controlling their relative movement and mechanism for controlling the grading device comprising an element arranged to be operatively related to the actuating mechanism at predetermined times.

71. In a machine of the class described, power driven mechanism comprising two carriages, a grading mechanism for controlling the movement of the carriages, means for controlling the grading mechanism comprising a part constructed and arranged to be projected into position to be engaged by a member of the power driven mechanism at a predetermined time.

72. In a machine of the class described, a power driven member, a plurality of moving carriages, a grading mechanism for controlling their relative movement and a control for said mechanism having a member arranged for unilateral engagement with the power driven member whereby said control may become operative at a predetermined time.

73. In a machine of the class described, a plurality of moving carriages, a power driven member, a grading mechanism for controlling their relative movement and a control for said mechanism having a member arranged for unilateral engagement with the power driven member during a portion of the operation of the machine, and means for holding said control immovable during the remainder of the operation.

74. In a machine of the class described, a power driven member, a plurality of moving carriages, a grading mechanism for controlling their relative movement and a control for said mechanism having a member arranged for unilateral engagement with the power driven member whereby a relative pressure between the member and the control will govern the control, and means for limiting the operation of such pressure at a predetermined point.

75. In a machine of the class described, power driven mechanism comprising a carriage on the model side and a carriage on the work side, a grading mechanism for effecting inequalities in the movements of the carriages, and a rate governor for the grading mechanism arranged for unilateral contact with an element of the power driven mechanism for controlling the movement of the governor, and means for limiting such contact.

76. In a machine of the class described, power driven mechanism comprising a carriage on the model side, and a carriage on the work side, a grading mechanism, a rate controller for the grading mechanism constructed and arranged to be contacted at a

predetermined point by an element of the power driven mechanism whereby said controller may be set in action.

77. In a machine of the class described, 5 power driven mechanism comprising a carriage on the model side, and a carriage on the work side, a grading mechanism, a rate controller for the grading mechanism constructed to press against an element of said power driven mechanism in the direction of its movement, means for operating said controller under the limitations imposed by said element, and means for limiting the operation of the controller at a predetermined 15 point.

78. In a machine of the class described, 20 model and work instrumentalities, a grading mechanism for causing relative movement between them, and a control for the grading mechanism, the combined grading mechanism and control being constructed and arranged for alinement with the center of the model used in the machine, irrespective of its length.

79. In a machine of the class described, 25 a carriage on the model side, a carriage on the work side, a grader for effecting relative movement between them, and a device for controlling the rate of grade, the grader 30 and the controlling device being severally adjustable longitudinally of the model.

80. In a machine of the class described, 35 a carriage on the model side, a carriage on the work side, two parallel members mounted on the frame and a grader and a grader control adjustably mounted on said members respectively, for controlling the relative movement of said carriages.

81. In a machine of the class described, 40 a carriage on the model side, a carriage on the work side, a grader constructed and arranged to effect substantially the same absolute variations between the work and the model regardless of the size of the latter, 45 and a rate controller for said grader constructed and arranged to effect its control irrespective of the size of the model.

82. In a machine of the class described, 50 carriages on the model and work side, respectively, grading mechanisms for controlling the relative movement of the carriages in two mutually transverse directions and a rate variation control for one of the grading mechanisms operating continuously during last cutting.

83. In a machine of the class described, 55 model holding and model guided instrumentalities, work and tool holding instrumentalities, means for effecting relative movements in more than one dimension between said instrumentalities in pairs, and mechanism for effecting a substantial variation during the cutting of the ratio between the components, parallel to one di-

mension, of corresponding relative movements in the pairs. 65

84. In a machine of the class described, 70 model holding and model guided instrumentalities, work and tool holding instrumentalities, means for effecting relative movements in two dimensions between said instrumentalities in pairs, and mechanism for effecting during the last cutting a substantial variation in the ratio between the components, in a fixed direction, of corresponding 75 movements between members of the pairs.

85. In a machine of the class described, 80 two carriages, a grading device connecting them, and mechanism for varying the uniformity of grade while the work is being formed.

86. In a machine of the class described, 85 a model wheel carriage, a cutter carriage, and a lever pivotally connected to each, said lever having a third pivot, and mechanism whereby the third pivot may be moved, if desired, toward or from one of the first-mentioned pivotal connections during the 90 turning of a last.

87. A machine of the class described having model and work holding instrumentalities, and model and work engaging instrumentalities, and mechanism for effecting relative movements between corresponding 95 instrumentalities in pairs, said mechanism having provision for adjustment whereby the velocity ratio between said relative movements may be made systematically non-uniform or approximately uniform, as desired. 100

88. In a machine of the class described, 105 model and work instrumentalities, and a grading mechanism controlling them and having provision for producing approximately geometrical or systematically non-geometrical correspondence between their movements in the direction of grade, as desired.

89. In a machine of the class described, 110 model and work instrumentalities, and a grading mechanism controlling them, said grading mechanism being convertible from approximately geometrical to distinctly non-geometrical performance, and vice versa.

90. In a machine of the class described, 115 relatively moving model and work instrumentalities, and a grading mechanism controlling the movement, comprising a lever the advantage of which may be rendered approximately constant or distinctly variable. 120

91. In a machine of the class described, 125 a model wheel carriage, a cutter carriage, mechanism connecting the carriages comprising a lever to which both are connected, and means operated by the movement of one carriage for variably controlling the relative leverage effect.

92. In a machine of the class described, a model carriage, a cutter carriage, a grading lever connecting the carriages, and means operated by one of the carriages for varying 5 the advantage of the lever.

93. In a machine of the class described, carriages on the model and work side, respectively, grading mechanisms for controlling the relative movement of the carriages 10 in two mutually transverse directions and a control for one of the grading mechanisms operating discontinuously during the cutting of a last.

94. In a machine of the class described, 15 carriages on the model and work side, respectively, grading mechanisms for controlling the relative movement of the carriages in two mutually transverse directions and a control for one of the grading mechanisms 20 operating continuously or discontinuously as desired.

95. In a machine of the class described, a model instrumentality, a work instrumentality, and a grading lever between said instrumentalities having a fulcrum connected to each and having a fulcrum, fixed in the lever, on the frame of the machine, the lever having a longitudinal movement and carrying said last-named fulcrum and one other 30 therewith during said movement, but not the third, so that a shift of leverage occurs as between the two first-named fulcrums.

96. In a machine of the class described, a carriage on the model side, a carriage on the 35 work side, and means for relatively moving said carriages comprising a lever rotatable about a fulcrum moving with relation to the connections between the two carriages to vary the leverage upon one with reference 40 to the other.

97. In a machine of the class described, two carriages, a grading lever, two pivots connected to the carriages respectively, a third pivot on the frame, and means for 45 justably connecting the lever to each of said pivots, which means includes possible relative leverage shifting movability for fulcrums during the cutting of a last as between the carriages, whereby ordinary or quite 50 non-uniform grading action may be secured as desired.

98. In a machine of the class described, a model carriage, a cutter carriage, a grading lever connecting the carriages, and means 55 operated by one of the carriages for varying the effective leverage as between the carriages.

99. In a machine for reproducing solid 60 objects, comprising four primary instrumentalities, viz., a model guide and a model holder, a tool and a work holder connected for relative movements to reproduce the model considered as an aggregate of differential elements, such elements being reproduced systematically in the work, means

which, for effecting non-geometric reproduction from the pattern as regards the relative positions of such reproduced differential elements in the work, determines differences in condition of adjustment in the copying 70 mechanism at predetermined times during the reproduction.

100. In a pattern reproducing machine comprising four primary instrumentalities, viz., a model guide and a model holder, a 75 tool and a work holder connected for relative movements to produce the model considered as an aggregate or differential elements, such elements being reproduced systematically in the work, a grading mechanism having variable leverage upon a plurality of the primary instrumentalities during the production of a work piece, whereby the reproduced differential elements are shifted relatively toward and from one another to effect non-geometric reproduction 80 from the pattern as regards the relative positions of such reproduced differential elements in the work.

101. That improvement in the art of 90 manufacturing lasts which consists in subdividing (in effect) the model into a system of differential elements, reproducing each element according to a systematic law, and automatically rearranging the reproductions 95 in the work in order in a relation to one another which has a substantially non-geometric relation to the relation between their prototypes in the model.

102. That improvement in the art of pattern 100 reproduction which consists in subdividing (in effect) the model into a system of differential elements, reproducing each element according to a systematic law, and rearranging the reproductions in the work 105 in order in relatively condensed and rarefied arrangement in different parts of the work, as compared with their prototypes in the model.

103. In a pattern copying machine, means 110 for holding a model and a work piece, and power-operated means for systematically reproducing the work, sections of the model and shifting any desired portion of such reproduced sections relatively to one another as they are formed.

104. In a three-dimensional pattern copying machine, means for holding a model and a work piece, and a grading mechanism and connections for pantographically reproducing in the work sections taken from the model and for automatically shifting such reproduced sections relatively to one another at a varying rate as they are formed. 120

105. In a three-dimensional pattern copying machine, means for holding a model and a work piece, and means for systematically reproducing in the work piece sections taken from the model and for predeterminedly shifting such reproduced sections non- 125 130

uniformly relatively to one another as they are formed.

106. In a three-dimensional pattern copying machine, means for holding a model and a work piece, and means for systematically reproducing in the work piece sections taken from the model and for shifting such reproduced sections at an arbitrarily predetermined non-uniform rate as they are formed.

107. In a pattern copying machine, means for holding a model and a work piece, a grading mechanism and connections for pantographically reproducing in the work piece sections of a model and for relatively shifting such reproduced sections relatively to one another, permitting an automatic change in the amount of relative shift at an intermediate point of the work.

108. In a three-dimensional pattern copying machine, guiding and cutting instrumentalities, model holding mechanism and block holding mechanism, constructed and arranged to present a model and a block of these instrumentalities respectively in similar relations, and means for varying the similarity of these relations during the production of a piece of work.

109. In a machine of the class described, guiding and cutting instrumentalities, model holding mechanism and block holding mechanism constructed and arranged to rotate and present a model and a block to said instrumentalities respectively in similar relations, and means for automatically varying the relations between said instrumentalities and said model and block in time relation to the longitudinal production of the work.

110. In a last lathe, guiding and cutting instrumentalities, model holding mechanism and block holding mechanism constructed and arranged to rotate and present the model to the guiding mechanism in operational relation and the block to the cutting mechanism in a similar relation respectively, and means for varying the similarity of these relations during the turning of a last.

111. In a last lathe, guiding and cutting instrumentalities, model holding mechanism and block holding mechanism, constructed and arranged to present a model and a block to these instrumentalities respectively in similar relations, and means for automatically varying the similarity of these relations at a desired rate during a desired portion of the cutting of a last.

112. That improvement in the art of pattern copying which consists in producing in a work piece systematic reproductions of substantially parallel sections of the model differentially and non-geometrically shifted relatively to one another.

113. That improvement in the art of pattern copying which consists in producing in a work piece systematic reproductions of substantially parallel sections of the model

differentially and non-geometrically shifted relatively to one another perpendicularly to their parallel dimensions.

114. That improvement in the art of copy turning which consists in automatically reproducing in a work piece pantographic reproductions of successive substantially parallel sections of a model and shifting them relatively to one another differentially, the rate of shift varying in different parts of the work.

115. That improvement in the art of manufacturing solid bodies which consists in presenting a block to a cutter and a model to a guide, governing the relation between the cutter and block by that between the model and guide to reproduce the model section by section, and causing variations in the relations between the four objects independent of the reproductional relative movement to effect a non-geometric relative shift between reproduced sections, said shift being substantially perpendicular to the sections.

116. In a three-dimensional pattern copying machine, model and block holding instrumentalities, model and block following instrumentalities, means for causing relative movement between the block and its following instrumentalities to effect a pantographic reproduction of the model providing for ordinary length grading, if desired, section by section, and connections for combining with such movement a movement effecting a relative shift between the reproduced sections.

117. In a three-dimensional pattern copying machine, a model holder, a model wheel, a block holder and a cutter, the relation between the block holder and cutter being pantographically controlled by the relation between the model holder and model wheel; and means for effecting a relative movement between a said controlled and a said controlling element to effect non-geometric relative shifting between differential elements in the reproduction.

118. In a three dimensional pattern copying machine, a model holder, a model wheel, a block holder and a cutter, the relation between the block holder and cutter being pantographically controlled by the relation between the model holder and model wheel, and providing for ordinary length grading; and a driving mechanism for effecting a relative movement between a said controlled and a said controlling element to effect relative shifting between differential elements in the reproduction.

119. In a three-dimensional pattern copying machine, a model holder, a model wheel, a block holder and a cutter, the relation between the block holder and cutter being pantographically controlled by the relation between the model holder and model wheel; and driving mechanism for causing a non-

uniform movement of one of the said elements independent of its behavior incident to the pantographic reproduction.

120. In a machine of the class described, 5 a model holder, a model wheel, a block holder and a cutter, the relation between the block holder and cutter being controlled by the relation between the model holder and model wheel; supporting and operating

10 mechanism for relatively moving said elements to effect pantographic reproduction in arbitrary proportions in length and width, and a driving mechanism intermediate between one of said elements and the 15 supporting and operating mechanism to effect relative shifting between differential elements in the reproduction.

121. In a machine of the class described, 20 a model holder, a model wheel, a block holder and a cutter, the relation between the block holder and cutter being pantographically controlled by the relation between the model holder and model wheel, supporting and operating mechanism for 25 relatively moving said elements to effect reproduction of differential elements and providing for relative separation or approach between the reproductions, and a mobile connection intermediate between one 30 of said elements and the supporting and operating mechanism to effect further relative shifting between differential elements in the reproduction.

122. In a machine of the class described, 35 a model holder, a model wheel, a work holder and a work contacting tool, supporting and operating means for these four instrumentalities constructed and arranged to cause relative pantographic reproductive 40 movement including ordinary length grading between the model instrumentalities and the work instrumentalities respectively,

the relation between the work instrumentalities being governed primarily by the relation between the model instrumentalities 45 to produce systematic reproduction of differential elements of the model in the work, and driving mechanism for compounding with the normal reproductive action of a said instrumentality a movement to effect 50 a shifting between reproduced differential elements in the work.

123. That improvement in the art of producing solid objects having a systematic resemblance to a solid pattern which consists in controlling the relation between the work and a work contacting tool by the relation between a model and model guide to reproduce differential elements of the model according to a pantographic law providing 60 for alteration in size in all dimensions, and effecting a movement of one of the said elements independent of its action incidental to pantographic reproduction to effect relative shifting of reproduced differential 65 model elements.

124. That improvement in the art of producing solid articles having a systematic resemblance to a solid pattern which consists in controlling the relation between the work 70 and a work contacting tool by the relation between a model and model guide to reproduce differential elements of the model according to a systematic law, providing, if desired, for longitudinal alteration in physical size of the model and effecting a relative movement between a controlled and a controlling element to effect additional relative shifting of reproduced differential 75 model elements.

In testimony whereof I have signed my name to this specification. 80

FREDERIC W. POTTER.
